UNITED STATES PATENT OFFICE.

ZALMON G. SHOLES, OF EVANSTON, ILLINOIS, ASSIGNOR TO THE UNION
TYPEWRITER COMPANY, OF NEW JERSEY.

TYPE-WRITING MACHINE.

SPECIFICATION forming part of Letters Patent No. 658,560, dated September 25, 1900.

Application filed January 10, 1898. Serial No. 666,261. (No model.)

To all whom it may concern:

Be it known that I, ZALMON G. SHOLES, a resident of Evanston, in the county of Cook and State of Illinois, have invented certain new and useful Improvements in Type-Writing Machines, of which I do declare the following to be a full, clear, and exact description, sufficient to enable others skilled in the art to make and use the same.

10 The present invention has relation more particularly to that class of type-writing machines commonly known as "pad-machines," in which provision is made for inking the type by means of an ink-pad, as distinguished 15 from the class of machines in which inking-ribbons are employed. The invention relates also particularly to that class of machines in which the printing-type are carried upon the ends of type-bars that are operated 20 by suitable lever mechanism of the keyboard of the machine.

One object of this invention is to provide improved mechanism whereby the type as they travel from the ink-pad to the platen 25 will be partially revolved, so that the face of the type will bear upon the ink-pad when at rest and will be so revolved as to be presented squarely to the platen when the type-bars are swung through the medium of the key-lever 30 mechanism and whereby undue revolution of the type-bar is prevented and the type are alined by a fixed guide arranged at the printing-point.

A further object of this invention is to provide a suitable curved or annular support or 35 holder for the ink-pad and means for stiffening the pad and means for feeding the pad into and out of its holder.

The invention consists in the features of construction hereinafter described, illustrated 40 in the accompanying drawings, and particularly pointed out in the claims at the end of this specification.

Figure 1 is a plan view of the type-plate of 45 a type-writing machine, the carriage mechanism being removed, showing the annular type-basket and the guide or directrix extending across the type-basket. Fig. 2 is a view in central vertical section from front to 50 rear of a type-writing machine embodying my invention. Fig. 3 is a detail plan view of one

of the type-bar hangers. Fig. 4 is a view in vertical section on line 4 4 of Fig. 3. Fig. 5 is a view in elevation of one of the type-bar hangers looking from the center of the machine outward. Fig. 6 is a detail view of the inner end of one of the type-bars, parts being broken away for better illustration. Fig. 6^a is a detail sectional at line 6^a 6^a of Fig. 6. Fig. 7 is a detail plan view of the ink-pad holder. Fig. 8 is a view of a portion of the ink-pad holder with the slide pushed back. Figs. 9 and 10 are side views of the ink-pad holder, the slide being shown as open and closed. Fig. 11 is a view in elevation of means 65 for inserting the ink-pad into its holder, a portion of the frame and holder being shown. Fig. 12 is a plan view of a portion of the ink-pad with the feeding-strip attached thereto. Fig. 13 is a detail view of a portion of the 70 blank from which the feed-strip of the ink-pad is made. Fig. 14 is a sectional view of the ink-pad with the feeding-strip attached thereto. Fig. 15 is a view in vertical cross-section and upon an enlarged scale on line 75 15 15 of Fig. 7.

A designates the frame of the machine, around the top opening or well of which the type-bars B are hung in circular series. Each of the type-bars B is provided at its 80 end with two type b b', as in the familiar "Remington Standard" machines. The inner end of each of the type-bars B is reduced, as at b², and of cylindrical outline and is pivotally held within a swinging box or support 85 C, as clearly shown in Fig. 6 of the drawings. Each of the swinging boxes or supports C is formed with an open space c to admit a bevel-pinion D, that is fixed to the reduced portion b² of the type-bar B. Each box or support C 90 is formed with trunnions c', adapted to fit into trunnion-seats e of the corresponding hanger E. The part C may therefore be termed a "pivoted yoke" or bearing-box for swinging the type-bar B to the printing-point and permitting it to revolve at the same time, and it is provided also with a tailpiece c², having the usual eye c³ for attachment to the rod, that is suitably joined to the corresponding key-lever F. The hangers E are of the construction shown more particularly in Figs. 3, 4, and 95 5 of the drawings, and these hangers are 100

5 mounted upon the top of the hanger-ring G, to which they are adjustably connected by screws *g*, that pass into the hanger-ring and through the cap-plates *g'*. Each of the hang-
 10 ers E has its rear portion of yoke shape and connected by a tie-rod *e'* or screw-bolt, and one side of the yoke-shaped hanger is ex-
 tended inwardly and curved downwardly, as at *e²*, to form a guide for the type-bars. The
 15 bodies of the type-bars B are flattened, as shown, so that as the bars are swung upward the flat side of the bars will bear against the
 20 guide-plates *e²*, and thus aid in securing the square delivery of the type against the platen.
 25 The extreme lower end of each guide *e²* is bent outwardly, so as to insure the passage of the corresponding type-bar along the side of the guide. Each of the hangers E is provided with a depending plate *e³*, the inner face of
 30 which is formed with a curved rack-bar *e⁴*, comprising a series of laterally-projecting teeth which are adapted to engage with the bevel-pinion D, that is fixed to the correspond-
 35 ing type-bar B.
 40 Across the central opening of the top plate of the machine extends a bar H, that is united, as by screws *h*, to the top plate, and this bar H is formed with two guide-holes *h'* and *h²* to receive the corresponding type *b* and *b'* of the
 45 type-bar. That part *h³* of the bar H that ex-
 50 tends between the holes *h'* and *h²* has its under portion formed with bevel-faces, as clearly seen in Fig. 2, in order to more accurately center or align the type with respect to the
 55 platen as the type are swung to the printing-
 60 point. By reference to Fig. 1 it will be seen that the holes *h'* and *h²* are oblong, since it is only necessary that two sides of the holes should act in guiding the type, the guiding
 65 of the type in opposite direction being effected by the part *h³*. In order to reduce as far as possible the width of the bar H without weakening the same, I prefer to arrange the holes *h'* and *h²* diagonally across the bar, as clearly
 70 seen in Fig. 1.

At a distance below the top of the main frame A is located a holder N for an annular ink-pad M, that is held in position by suitable supports *m* and at such point that the
 75 pad will serve as a bearing for the type when the type-bar is at rest.

From the foregoing construction it will be seen that when the type-bars are in normal position all the type will rest against the face of the annular ink-pad M and will receive ink therefrom. If, now, one of the key-levers F be depressed, the corresponding type-bar B will be thrown upward toward the platen, and as the type-bar thus moves upward the
 80 travel of the bevel-pinion D over the rack-bar *e⁴* will cause a half-revolution of the type-bar, so as to bring the type *b b'* in position to contact with the platen whereby the paper to be printed upon is carried. As the types
 85 *b b'* are thus moved toward the platen they will enter the holes *h' h²* of the guide-bar H and upon either side of the beveled cross-bar

90 *h³*. The types will thus be accurately di-
 95 rected at the final end of their upward move-
 ment, thereby securing an accurate aline-
 ment of the printing. As is well known, in
 100 the Remington machine a cylindrical platen
 is arranged transversely of the machine to
 receive the impact of the types and in the
 105 normal position of the platen only one of the
 two types on a bar can strike. When the
 110 platen is shifted rearwardly, only the other of
 115 said types can strike. When pressure upon
 the key-lever F is released, the type-bar B
 120 will be retracted in the usual manner, and
 as the type-bar B moves downward the pas-
 125 sage of the beveled pinion D along the rack-
 bar *e⁴* will effect a half-revolution of the type-
 130 bar and types, thereby causing the types to
 bear against the face of the ink-pad M. By
 135 forming the rack-bar *e⁴* upon the inner face
 of the depending portion *e³* of each of the
 140 hangers E these rack-bars can be stamped
 with great accuracy and but slight cost from
 the plates.

In order to facilitate the introduction of the ink-pad M into its annular holder N, I prefer to employ the mechanism hereinafter de-
 145 scribed and to construct the holder as here-
 150 inafter set forth. The body of the holder N
 is preferably of sheet metal, and its upper and
 155 lower edges are shaped to receive and retain
 in place the ink-pad M. In the outer face of
 the holder N is formed an opening *n*, through
 160 which the ink-pad will be inserted, and in the
 top edge of the holder above the opening *n* is
 165 formed a slot *n'*, the purpose of which will
 presently appear. The openings *n* and *n'*
 170 may be closed by a sliding cover N', prefer-
 ably formed of sheet metal, the upper and
 175 lower edges of which are bent to overlap the
 top and bottom of the holder N, as shown.
 At one side of the opening *n* there is a raised
 180 stop or offset *n²* to limit the movement of the
 slide-cover N', and at the rear edge of the
 185 slide-cover a notch *n⁴* may be formed to per-
 mit the easy shifting of the cover. The pur-
 190 pose of the long slot *n'* of the holder N and
 the slot *n⁵* of the cover N' is to admit the
 195 teeth of a spur-wheel P, that is carried upon
 the end of the shaft *p*, revolvably mounted at
 the upper end of a bracket R, the outer end
 200 of the shaft *p* having fixed thereto a crank
p', whereby the shaft and wheel may be
 turned. The lower end of the bracket R is
 205 attached to one of the side bars of the main
 frame and will be held in place thereon by a
 screw *r*. Preferably the ink-pad before its
 210 insertion into the holder N will be partially
 inclosed within a sheet-metal strip S. (See
 215 Figs. 12, 13, and 14.) The upper edge of this
 strip S may be formed with teeth *s*, which
 220 when bent over the top edge of the pad will
 constitute a rack-bar with which the teeth of
 225 spur-wheel P will mesh, and preferably the
 lower edge of the strip S will also be formed
 of teeth *s'*, that will be slightly embedded in
 230 the lower edge of the pad M, and thus more
 securely retain the pad upon the strip S. The

cutting away of the edges of the strip S permits the strip to be more readily bent, so as to fit within the annular pad-holder. After the strip S has been attached to the pad M in manner last described one end of the pad and strip will be placed within the opening n of the holder N, so that the teeth s of the strip S will be engaged by the spur-wheel P, after which by turning the crank p' the spur-wheel P will cause the strip S and pad M to pass completely into the holder N.

It is obvious that in attempting to insert a pad into the holder N from the inside it would be necessary either to remove the type-bars from the machine or to adopt some means for temporarily bunching together the type ends thereof about centrally of the machine, which would batter the types and perhaps bend some of the type-bars. By the described construction the pad is quickly inserted from the outside without removing the type-bars or bunching them. A distinct and further advantage is gained by inserting the pad endwise into the annular or curved holder, as the end of the pad can be readily threaded or passed between the usual type-bar connections or other parts of the machine and inserted into the holder, and the pad can then be readily fed around either in the described manner or otherwise. The cover N' affords a support for that portion of the yielding pad which remains opposite the opening n made for its insertion.

It is obvious that certain features of the invention may be employed without the others.

Having thus described my invention, what I claim as new, and desire to secure by Letters Patent, is—

1. In a type-writing machine, the combination of a type-bar, a pinion fixed to said type-bar, a pivoted yoke or bearing-box whereon said type-bar is revolubly mounted, a hanger wherein said yoke or bearing-box is journaled, one of the arms of the hanger being provided with a curved rack meshing with the teeth of said pinion only at the initial portion of the movement of the type-bar toward the printing-point, whereby the type-bar is caused to revolve in the bearing-box, and means coöperating with the shank of the type-bar for thereafter guiding the type-bar to prevent revolution thereof during the remaining portion of its movement to the printing-point, substantially as described.

2. In a type-writing machine, the combination of a type-bar, a pinion fixed to said type-bar, a pivoted yoke or bearing-box whereon said type-bar is revolubly mounted, a hanger wherein said yoke or bearing-box is journaled, one of the arms of the hanger being provided with laterally-projecting teeth meshing with the teeth of said pinion only at the initial portion of the movement of the type-bar toward the printing-point, whereby the type-bar is caused to revolve in the bearing-box, and means coöperating with the shank of the type-bar for thereafter guiding the type-bar

to prevent revolution thereof during the remaining portion of its movement to the printing-point, substantially as described.

3. In a type-writing machine, the combination of a type-bar, a pinion fixed to said type-bar, a yoke or bearing-box wherein said type-bar is revolubly mounted, and a hanger wherein said bearing-box or yoke is journaled, one of the arms of said hanger being extended and provided with a rack-bar adapted to mesh with said pinion to rotate it during the initial swinging movement of said type-bar, and said arm of said hanger being further extended and provided with a depending guide-arm constructed to prevent the revolution of the type-bar when the rack is out of mesh with the pinion, substantially as described.

4. In a type-writing machine, the combination of a type-bar, a pinion fixed to said type-bar and movable therewith, means for swinging the type-bar, a stationary rack for engaging said pinion, and a stationary guide forward of the rack and arranged to act upon a revoluble shank portion of a type-bar to direct its type properly toward the printing-point after the rack has ceased to turn the said pinion, substantially as described.

5. In a type-writing machine, the combination of a bar, a pinion fixed thereto, means for engaging the pinion to rotate it, a yoke or bearing-box whereon said bar is revolubly mounted, a hanger wherein said yoke or bearing-box is journaled, whereby said bar may be swung to the printing-point, a plurality of types arranged on the free end of said bar, and a fixed guide for the types arranged in proximity to the printing-point and including a tapering member, as h³, constructed to enter the space between the types and thereby aline them, substantially as described.

6. In a type-writing machine, the combination of a bar, a pinion fixed thereto, a yoke or bearing-box whereon said bar is revolubly mounted, a hanger wherein said yoke or bearing-box is journaled whereby the bearing-box and bar may be swung together toward the printing-point, means for engaging the pinion to rotate it during the initial portion of the movement of the bar toward the printing-point, a stationary arm coacting with the shank of the type-bar for preventing revolution of the bar during the latter portion of its movement to the platen, a type fixed upon the free end of the bar, and a fixed guide arranged in proximity to the printing-point for alinement of the type, substantially as described.

7. In a type-writing machine, the combination with a type-bar having a flat side, of a pinion fixed to said type-bar and movable therewith, a rack-bar engaging said pinion, and a guide-arm against which said type-bar will bear as the pinion passes from engagement with the rack-bar, substantially as described.

8. In a type-writing machine, the combina-

tion with a type-bar provided with two types, the bodies of which are arranged at a distance apart, of a center guide for said types comprising a bar extending across the type-basket, said bar being provided at its center with two holes for the types, said holes being of a width adapted to snugly inclose the types and thus secure their alinement in one direction and being provided with an intermediate part having downwardly-inclined sides and adapted to snugly fit between the type-bodies, substantially as described.

9. In a type-writing machine, the combination with a series of types, of a curved or annular ink-pad holder arranged exteriorly thereof and open upon its inner side, and an ink-pad arranged within said holder to ink the types upon their return to normal position, said ink-pad holder being provided upon its outer side with an opening for the introduction and removal of said ink-pad, substantially as described.

10. In a type-writing machine, the combination with a series of types, of a curved or annular ink-pad holder arranged exteriorly thereof and open upon its inner side, an ink-pad arranged within said holder to ink the types upon their return to normal position, said ink-pad holder being provided upon its outer side with an opening for the introduction and removal of said ink-pad, and a cover for said opening, substantially as described.

11. In a type-writing machine, the combination of a curved or annular ink-pad holder, and a curved or annular ink-pad provided with a metal strip having bent edges which engage the edges of said ink-pad to stiffen the same so as to permit the ink-pad to be readily inserted into and removed from the holder by endwise movements, substantially as described.

12. In a type-writing machine, the combination of a series of types arranged in a curve or circle, a curved or annular ink-pad holder arranged in proximity to the types, an inking-pad, and mechanical devices for feeding the pad endwise into and out of the holder, substantially as described.

13. In a type-writing machine, the combination of a series of types arranged in a circle, an inking-pad having ends, and an annular pad-holder arranged around the types and in proximity thereto and having an opening from the outside for the insertion of one end of the ink-pad, whereby the pad may be inserted endwise in the holder without bunch-

ing the types together or removing them from the machine, substantially as described.

14. In a type-writing machine, the combination of a series of types arranged in a curve or circle, an inking-pad having ends, and a curved or annular pad-holder arranged in proximity to the types and having an opening in that portion which is farthest from the types, whereby the pad may be inserted endwise in the holder without bunching the types or removing them from the machine, substantially as described.

15. In a type-writing machine, the combination of a series of types arranged in a circle, an inking-pad having ends, an annular pad-holder arranged around the types and in proximity thereto and having an opening on the outside for the insertion of the pad whereby the pad may be inserted endwise in the holder without bunching the types together or removing them from the machine, and a cover for said opening to form a support for the pad, substantially as described.

16. In a type-writing machine, the combination with an ink-pad, of a metal strip having toothed edges adapted to be bent over the edges of the pad, whereby said pad is stiffened and whereby one of its edges is provided with a toothed surface to permit the pad to be readily inserted into a holder, substantially as described.

17. A means for inserting an ink-pad into its holder comprising a spur-wheel or pinion, a shaft and crank for operating the same and a bracket for sustaining said shaft, substantially as described.

18. In a type-writing machine, the combination with an ink-pad holder having an opening in its upper edge, of a spur-wheel or pinion adapted to enter said opening and engage the pad within the holder, a crank and shaft for turning said spur-wheel or pinion and a suitable support for said crank or shaft, substantially as described.

19. The combination with an ink-pad, of a metal strip having a toothed upper edge, a holder for receiving said ink-pad, a spur-wheel or pinion for engaging the toothed edge of the metal strip, a crank and shaft for turning said pinion and a bracket or support for said shaft, substantially as described.
